[57] ABSTRACT

Leaf spring having at least one lead and a fastening clip in the centre part of the leaf or leaves. A corrugation extending throughout the width of the leaf or leaves adjoins two corrugations in the clip on each side of the leaf or assembled leaves.

**LEAF SPRING HAVING AN IMPROVED
FASTENING CLIP**

The present invention relates to vehicle suspension leaf springs comprising at least one leaf and interposed between the suspended part and the unsuspended part of the vehicle.

In such springs, it is known that the leaves are surrounded in their centre part by a forged cage termed a clip and are centered with respect to each other and with respect to the clip by bolts or indentations. When bolts are used as centering means, it is necessary to provide apertures in the leaves and this of course results in a reduction in the section of each leaf and consequently weakens the spring. To a less extent the use of indentations also results in a discontinuity which weakens the leaves concerned. It is then necessary, in order to obtain sufficient strength in the centre part of this spring, to embed it in a long clip which reduces the flexibility.

The advantages afforded by a preforming of the spring are known as concerns the increase in the allowable load and above all the life of the spring. This operation is carried out in the cold state by applying to the spring an overload so as to exceed the elastic limit of the metal and produce plastic deformations. In order that this operation be effective, the whole of the useful part of the spring must be subjected to this load exceeding the elastic limit. Now, the clip of the spring is never perfectly rigid and the spring is not completely embedded therein, above all now that it is desired to render such assemblies lighter and consequently employ short clips having low rigidity, and is therefore necessary to produce also a preforming in the region inside the clip. When the leaves are provided with apertures for the passage of bolts or are deformed by the presence of indentations, when the preforming operation is carried out, the elastic limit is reached sooner in the section in which the aperture or indentation is located than in other parts of the spring. Consequently, the spring is deformed plastically in this centre region whereas the remainder of the spring hardly reaches the elastic limit and undergoes practically no plastic deformation. It is practically impossible to increase the preforming force otherwise there is a danger of initiating a split or crack in the section weakened by an aperture or indentation. This splitting being moreover encouraged by the sudden change in section.

An object of the invention is to provide a centering and fastening device for a leaf spring which does not reduce the section of the spring or result in sudden variations which permits the utilization of relatively short clips and which also permits the submission of the spring to a preforming operation over its entire length so as to ensure a substantially prolonged spring life.

The invention provides a leaf spring comprising at least one leaf and a detachable fixing clip disposed in the centre part of the spring, wherein the or each leaf has in its fastened or clipped centre part a corrugation extending throughout its width, the clip having on each side of the spring two faces having corrugated portions of corresponding shape.

In view of the fact that these corrugations extend throughout the width of the or each leaf, any discontinuity in the section and any preferential fracture region is avoided.

Further features and advantages of the invention will be apparent from the ensuing description with reference to the accompanying drawing.

In the drawing:

5 FIG. 1 is a longitudinal sectional view of a first embodiment of a leaf spring according to the invention;

FIG. 2 is a sectional view taken along line 2-2 of FIG. 1;

10 FIGS. 3 and 5 are views similar to FIG. 2 of modifications, and

FIGS. 4 and 6 are sectional views taken along lines 4-4 and 6-6 of FIGS. 3 and 5.

15 FIGS. 1 and 2 show a spring R₁ comprising respectively a single leaf 1 which has at its ends fixing eyes 2

and is integral in its centre portion with a fastening clip 3. The leaf 1 has in the centre portion a corrugation 1a whose concavity is upwardly facing in the presently described embodiment, that is, it has the same orientation

20 as the whole of the spring. The clip 3 is composed of two parts 4 and 5 having a U-shaped section (FIG. 2), these two parts 4 and 5 having in the web portion thereof 4a, 5a, a corrugation corresponding to the corrugation 1a of the leaf and being provided in their flanges 4b, 5b, with apertures 4c, 5c, for the passage of

25 suitable fixing means.

In the embodiment shown in FIGS. 3 and 4, the illustrated spring R₂ has two leaves 11, 12, which are corrugated in their centre part and the fastening clip 13 is constructed in a somewhat different way. This clip 13 is in one piece and defines two corrugated strips 13a, 13b, which are disposed on each side of the leaves and flanges 15a, 15b, which extend in a direction perpendicular to the leaves and are provided with openings 16 for the passage of fixing means.

30 35 The spring R₃ shown in FIGS. 5 and 6 also has two leaves 21, 22, which are corrugated in their centre part and the fastening clip 23 is so constructed as to permit a different fixing method, two fixing tabs 24a, 24b extending from the upper strip of the clip in a direction parallel to the plane of the leaves.

40 It will be understood that these various modifications, which concern the number of leaves of which the spring may be composed, the particular construction of the clips and especially the position of the means for fixing it on an axle or other part of a vehicle, are not critical and may be subjected to various other modifications. The essential feature of the invention in all these embodiments resides in the fact that the centering of the leaves with respect to each other and with respect to the clip is achieved by forming in the leaves and in the adjacent strips of the clip corrugations which extend throughout the width of the leaves and therefore do not constitute a region of reduced section which would weaken the spring. The utilization of such centering means enables relatively short clips to be employed so that maximum resiliency of the spring is achieved. Owing to this arrangement, it is also possible to impart to the spring a preformation which is roughly the same throughout its length and thereby substantially prolong its life. It has been found that it is possible to increase this preforming load by 30 - 50 percent without danger, which increases the elastic limit of the spring correspondingly. Specific trials have shown that,

60 65 for a given load, the life of a spring according to the invention, measured by the number of oscillation cycles before fracture under given bending conditions, was of the order of 300,000 - 500,000 cycles whereas usually

the life of a conventional spring is of the order to 100,000 cycles. This clearly reveals the importance of the improvement both from the viewpoint of performance and reliability and the viewpoint of cost.

Having now described my invention what I claim and desire to secure by Letters Patent is :

1. A leaf spring structure comprising at least one leaf, a corrugation extending throughout the width of the leaf in a centre part the latter the latter and a detachable fastening clip disposed in a centre part of the spring, said clip comprising two flanges which extend each in one side of said spring in a direction perpendicular to the plane of the leaf, two bearing surfaces extending from one flange to the other and each adjoining one opposite face of said spring, fixing tabs fast to said flanges, means defining apertures in these tabs for the passage of fixing means and corrugations in each of said bearing surfaces, said corrugations having a shape corresponding to the corrugation of the leaf.

2. A leaf spring structure as claimed in claim 1, wherein the clip comprises two members, one inside

the other, each member having two flanges and a web portion interconnecting the flanges and defining a U-shaped cross section, bearing surfaces on said two web portions adjoining opposite faces of the spring and being corrugated, the flanges of outer member extending beyond the inside member and forming two first fixing tabs and the flange of inside member forming two second fixing tabs parallel to the first, one on each side of the spring, and means defining apertures in said tabs for the passage of fixing means.

3. A leaf spring structure as claimed in claim 1, wherein the clip is in one piece and has two corrugated strip portions disposed on each side of the leaf and two flanges which extend in a direction perpendicular to the plane of the leaf and have apertures for the passage of fixing means.

4. A leaf spring as claimed in claim 1, wherein the clip comprises two fixing tabs which extend from an upper part of the clip in a direction parallel to the plane of the leaf.
